[57] CLAIM

The ornamental design for a lens member for a motor vehicle headlighting system, as shown and described.

DESCRIPTION

FIG. 1 is a front perspective view of a lens member for a motor vehicle headlighting system, illustrating our new design;

FIG. 2 is a top plan view thereof;

FIG. 3 is a cross-sectional view as taken along line 3—3 in FIG. 5, on an enlarged scale;

FIG. 4 is a side perspective view as seen from the left in FIG. 1, on an enlarged scale; and

FIG. 5 is a rear elevational view thereof, on a reduced scale.

FIG.1

FIG.2

FIG. 3

FIG. 4

FIG. 5
